F. W. WOLFE,

CAR ROOF.

APPLICATION FILED JULY 5, 1919.

1,315,807.

Patented Sept. 9, 1919.

UNITED STATES PATENT OFFICE.

FRANK W. WOLFF, OF PARNASSUS, PENNSYLVANIA, ASSIGNOR TO P. H. MURPHY COMPANY, OF PARNASSUS, PENNSYLVANIA, A CORPORATION OF PENNSYLVANIA.

CAR-ROOF.

1,315,807.

Specification of Letters Patent.

Patented Sept. 9, 1919.

Application filed July 5, 1919. Serial No. 308,838.

To all whom it may concern:

Be it known that I, FRANK W. WOLFF, a citizen of the United States, and a resident of the city of Parnassus, in the county of 5 Westmoreland and State of Pennsylvania, have invented a new and useful Improvement in Car-Roofs, of which the following is a specification.

This invention relates principally to metal 10 car roofs of the all-steel riveted-up type wherein self-supporting roof sheets extend from side plate to side plate of the car and have their side margins raised, lapped and riveted together forming seams which function as carlines.

One of the principal objects of the present invention is to enable the roof sheets to be pressed from a rectangular plate, that is, a blank sheet having parallel sides, thus eliminating the expense of shearing the blank to 20 special shape before pressing. Another object is to produce a seam construction which will be of suitable section at the ridge of the car to withstand the vertical roof load at 25 this point and which will gradually change into a broad flat section at the eaves to withstand horizontal stresses resulting from the racking and weaving of the car frame. Another object is to provide a supporting member 30 at the eaves of the car, which will afford a wide flat bearing and riveting area for the roof sheets in the region of the seam and minimize the stresses in the sheets in the region of the rivets, which secure the vertical down-turned eaves ends of the sheet to the side plate. Another object of the supporting member is to take care of any leakage 35 which might occur at the lapped seam flanges where they are turned down over the eaves due to a possible misfit, which is liable 40 to be caused by imperfectly formed parts or by the buckling of the parts when the rivets are drawn up. Another object is to simplify the construction of the roof and to cheapen 45 the cost of manufacturing the same.

The invention consists in an all-metal car roof wherein the roof sheets extend across the car and have their side margins raised, lapped and riveted to form hollow seams 50 which function as carlines, the seam being of greater height at the ridge than at the eaves and being of greater width at the eaves than at the ridge. The invention further consists

in the combined supporting and flashing member for the eaves end of the seams and 55 in the combinations and arrangements of parts hereinafter described and claimed.

In the accompanying drawings, wherein like symbols refer to like parts wherever they occur,

Figure 1 is a plan view of a portion of a car roof embodying my invention, parts being shown broken away to more clearly illustrate the invention;

Fig. 2 is a transverse section through the 65 roof, the section being taken on the line 2—2 in Fig. 1;

Fig. 3 is an enlarged cross-section through the eaves portion of the roof, the section being taken lengthwise of one of the seams on 70 the line 3—3 in Fig. 1;

Fig. 4 is a cross-section through the eaves portion of the roof, the section being taken between seams on the line 4—4 in Fig. 1;

Fig. 5 is a longitudinal section taken 75 through the roof at the ridge crosswise of a seam on the line 5—5 in Fig. 1;

Fig. 6 is a cross-section of a seam, the section being taken midway between the ridge and eaves of the roof on the line 6—6 in Fig. 80 1; and

Fig. 7 is a longitudinal section through the roof at the eaves, the section being taken through a seam and supporting angle on the line 7—7 in Fig. 1.

The roof illustrated in the accompanying drawing comprises transversely arranged load-sustaining roof sheets 8, which extend from eaves to eaves of the car and have downwardly extending flanges 9 at their eaves ends. The roof sheets are supported on Z-bar side plates 10 which have their web portions disposed horizontally and have 90 their inner flanges uppermost and their outer flanges lowermost. The roof sheets are pressed from a single piece of metal of uniform width and their side margins are raised above the plane of the body of the sheet forming outwardly extending horizontal flanges 11, which are connected to the body 100 of the sheet by parallel web portions 12, forming side marginal flanges of substantially inverted L-shaped section. The web portions 12 of the side marginal flanges of the sheet gradually diminish in height from 105 the ridge toward each end and the surplus

metal, resulting from this tapering of the web portion 12 by reason of pressing the sheet from a rectangular piece of metal, causes the horizontal flange 11 at each side 5 of the sheet to widen out uniformly as the depth of the web portion decreases until the flange 11 reaches a point adjacent to the eaves end of the sheet where it merges into the plane of the body sheet.

10 The roof sheets are lapped along their side margins and the raised side marginal flanges 11 are rigidly secured together by means of rivets 13 forming seams of inverted channel-shaped section which function as carlines 15 and whose depth decreases from the ridge toward the eaves and whose width increases from the ridge toward the eaves.

The widening out of the lapped flanges 11 of the seam, which constitutes the carline, 20 from the ridge toward the eaves allows additional riveting space and permits two rows of the rivets 13 to be used for securing the lapped flanges together. Preferably, the row of rivets which secures the open side of 25 the seam has a greater number of rivets, for the purpose of securing a water tight joint, than the opposite row which secures the marginal edge of the underlapping flange to the overlapping flange of the adjacent sheet, 30 the purpose of this last mentioned row being to render the seam more rigid.

A supporting and flashing member 14 of angular section is located under the eaves ends of the sheet at their lapped portions and 35 extends a short distance beyond the seam on each side thereof. The vertical flange of each of these angles is located outside of the innermost flange of the Z-bar side plates 10 and is secured thereto, together with the 40 downwardly extending lapped flanges 9 at the ends of the roof sheet, by means of rivets 15, which also secure the eaves flanges 9 of the sheets to the innermost flange of the Z-bar side plates between seams. The other 45 flange of the angle 14 projects inwardly, parallel with the body portion of the sheets, over the upper edge of the innermost flanges of the Z-bar side plates and the lapped flanges 11 at the side margins of the sheets, 50 together with the adjacent body portion of the sheets at each side thereof, are secured thereto by means of rivets 16. These rivets, which secure the lapped seam flanges 11, are preferably provided with washers 17, which 55 act as spacers and supports for the top of the roof seam and also afford aid in riveting.

The running boards 18 are arranged lengthwise of the car and are securely bolted to the lateral flanges of the channel-shaped 60 metal running-board saddles 19. The running-board saddles 19 rest on and are riveted to the lapped seam flanges 11 by means of the rivets 13 which also secure said flanges together.

65 With the foregoing described arrange-

ment, it is evident that the lapping and riveting together of the L-shaped side marginal flanges of the sheets, which form carlines of channel section, produces a rigid structure well adapted to withstand the vertical roof 70 loads while the widening out of the seam toward the eaves functions after the manner of a gusset and produces wide end portions for attachment to the side plate and also takes care of the horizontal stresses which 75 the car may be subjected to while in service.

The angle members 14 located under the seams at the eaves of the car support the roof sheets and relieve the down-turned eaves flanges 9 of the roof sheet, which are 80 riveted to the vertical flanges of the Z-bar side plates 10, of the greater portion of the weight of the roof, and also afford additional means for securing the sheets at the eaves. By reason of the angle members 14 85 being located directly under the lapped seam flanges 11, with their vertical flanges located outside of the vertical flanges of the Z-bar side plates, a flashing effect is obtained whereby any water, which may enter between the lapped seam flanges 11 where they are turned over the eaves due to an imperfect fit, is caused to flow out over the side plate flanges.

The shape of the side marginal flanges of 95 the sheets permits use of all of the metal contained in a sheet blank of rectangular shape without the expense of trimming the blank to a special shape before pressing.

It is evident that the supporting angle 100 bracket 14 is applicable for use in connection with roofs having side plates and seams of various sections; also that the roof itself is applicable to various designs of supporting framing; therefore, I do not wish to be limited to the details of the construction.

What I claim is:

1. A car roof comprising metal roof sheets 110 extending from eaves to eaves, the side margins of the respective sheets being raised above the body of said sheets and being lapped and secured together to form seams, the extent of the seam lap being greater at the eaves than at the ridge.

2. A car roof comprising metal roof sheets 115 extending from eaves to eaves, the side margins of the respective sheets being raised above the body of said sheets and being lapped and secured together to form seams, the raised side margins of the sheets being 120 closer to the body of the sheets at the eaves than at the ridge and the extent of the seam lap being greater at the eaves than at the ridge.

3. A car roof comprising metal roof sheets 125 extending from eaves to eaves, the side marginal portions of said sheets being disposed above the body of the sheets at the ridge and merging into the body of the sheets adjacent to the eaves, said side marginal portions of 130

- said sheets being lapped and secured together to form seams, the extent of the seam lap being greater at the eaves than at the ridge.
5. A car roof comprising metal roof sheets extending from eaves to eaves, the side margins of the respective sheets being raised above the general plane of the sheets at the ridge and gradually approaching and merging into the body of the sheet adjacent to the eaves, said raised side margins of the sheets being lapped and secured together to form seams, the extent of the seam lap increasing correspondingly in width as the 10 raised side marginal portions of the sheets approach the body of the sheet.
5. A car roof comprising metal roof sheets extending from eaves to eaves, the side margins of the respective sheets being raised above the body of the sheets at the ridge and gradually approaching and merging into the body of the sheet adjacent to the eaves, the end portions of said sheets being bent down over the side walls of the car and rigidly 15 secured thereto, said raised side margin of the sheets being lapped and rigidly secured together to form seams, the extent of the seam lap increasing correspondingly in width as the raised side marginal portions of 20 the sheets approach the body of the sheet.
6. A car roof comprising metal roof sheets extending from eaves to eaves, the side marginal portion of the respective sheets being disposed above the body of the sheets at the ridge and merging into the body of the sheets at the eaves, said side marginal portions of said roof sheets being wider at the eaves than at the ridge and being lapped and secured together to form seams which 25 constitute load carrying members, said seams being of greater depth at the ridge than at the eaves and being of greater width at the eaves than at the ridge.
7. A car roof comprising transversely arranged metal roof sheets having their side margins connected together to form raised seams which constitute load carrying members, said seams being wider at the eaves than at the ridge.
- 50 8. A car roof comprising metal roof sheets extending from eaves to eaves and connected along their side margins by raised seams which constitute load carrying members, said seams being of greater depth at the ridge than at the eaves and being of greater width at the eaves than at the ridge.
9. A car roof comprising metal roof sheets extending from eaves to eaves and secured thereto, the side margins of the respective sheets having outwardly projecting flanges disposed above the body portions of the sheets and connected thereto by web portions, said web portions being of greater depth at the ridge than at the eaves.
- 55 10. A car roof comprising metal roof sheets extending from eaves to eaves and secured together to form seams, the extent of the seam lap being greater at the eaves than at the ridge.
11. A car roof comprising metal roof sheets extending from eaves to eaves, the side margins of the respective sheets having outwardly projecting flanges disposed above the body portions of the sheets and connected thereto by substantially vertical web portions, said flanges being wider at the eaves than at the ridge.
12. A car roof comprising metal roof sheets extending from eaves to eaves, the side margins of the respective sheets having outwardly projecting flanges disposed above the body portions of the sheets and connected thereto by upstanding web portions, said web portions being of greater depth at the ridge than at the eaves and said outwardly projecting flanges being of greater width at the eaves than at the ridge.
13. A car roof comprising metal roof sheets extending from eaves to eaves, the side margins of the respective sheets having outwardly projecting flanges disposed above the body portions of the sheets and connected thereto by upstanding web portions, said flanges being inclined toward the body of the sheets on opposite sides of the ridge and merging into the body of the sheets adjacent to the eaves ends thereof.
14. A roof sheet for a car roof, said roof sheet having flanged portions at its side marginal edges adapted to coöperate with a similar flanged portion of an adjacent sheet to form a seam, said flanges being of greater width at the eaves than at the ridge.
15. A roof sheet for a car roof, said roof sheet having flanged portions at its side marginal edges adapted to coöperate with a similar flanged portion of an adjacent sheet to form a seam, said flanges being of greater height at the ridge than at the eaves and being of greater width at the eaves than at the ridge.
16. A roof sheet for a car roof, said roof sheet being adapted to extend from eaves to eaves of the car and having raised flanges at its side margins adapted to coöperate with a similar flange of an adjacent sheet to form a connection therewith, said raised flanges being of greater width at the eaves than at the ridge.
17. A roof sheet for a car roof, said roof sheet being adapted to extend from eaves to eaves of the car and having side marginal

4

flanges disposed above the body portion of the sheet and connected thereto by upstanding web portions, said flanges being adapted to coöperate with the flanges of adjacent sheets to form a connection therewith and gradually approaching the body portion of the sheet on opposite sides of the ridge thereof and merging into the body of said sheet adjacent to the ends thereof and being of greater width at the eaves than at the ridge.

18. A roof sheet for a car roof, said roof sheet being adapted to extend from eaves to eaves of the car and having down-turned flanges at its eaves ends for securing the sheet to the sides of the car, said sheet having side marginal flanges disposed above the body of the sheet at the ridge and connected thereto by upstanding web portions and being adapted to be lapped and rigidly connected to similar flanges of adjacent sheets, said flanges merging into the body of the sheet adjacent to the eaves ends thereof and being of greater width at the eaves than at the ridge.

19. A roof sheet for a car roof, said roof sheet being adapted to extend from eaves to eaves of the car and being pressed from a single piece of metal of uniform width, said roof sheet having upstanding parallel web portions at its side margins of diminishing depth from the middle toward each end, the surplus metal obtained thereby being formed into a flange extending outwardly from the top of the web portion at the side of said sheet and being of greater width at the ends of the sheet than at its middle.

20. A car roof comprising roof sheets extending from side plate to side plate and secured thereto along their ends, said roof sheets being connected along their side margins by lap-joints, and a supporting member attached to the side plate at each of said joints, said supporting member extending on opposite sides of the joints and having an inwardly extending portion adapted to support the sheets in the region of the joints.

21. A car roof comprising roof sheets extending from side plate to side plate and having their ends turned down and rigidly secured to the outer face of said side plate, said roof sheets having their side margins raised and lapped and secured together to form rigid joints, and a supporting member secured to the side plates at each joint, said supporting member being arranged between the lapped turned down ends of the roof sheets and the outer face of the side plates and having a portion projecting inwardly beneath the lapped portions of the roof sheets to support the seam and being rigidly secured thereto.

22. A car roof comprising roof sheets extending from side plate to side plate and

having their ends turned down and rigidly secured to the outer face of the side plate, said roof sheets having their side margins raised above the plane of the sheets and lapped and secured together to form rigid joints, the extent of the lap being greater at the eaves than at the ridge, and a supporting angle attached to the side plate at each lapped joint, said supporting angle having its vertical flange arranged between the down-turned end of the sheets and the outer side of the side plate and having its other flange projecting inwardly beneath and secured to the lapped portions of the roof sheets, a portion of the sheets at each side of the lapped portions being also secured to said supporting angle.

23. A car roof comprising roof sheets extending from side plate to side plate, and a supporting member attached to the side plates at each of the transverse roof joints and having an inwardly extending portion adapted to support the sheets in the region of the joints.

24. A car roof comprising roof sheets extending from side plate to side plate, and having their ends turned down and rigidly secured to the outer faces of the side plates, said roof sheets being connected along their side margins by rigid standing seams constituting load carrying members, and a combined supporting and flashing member secured to the side plates beneath each seam, said supporting member being arranged between the down-turned ends of the roof sheets and the outer faces of the side plates and having a portion projecting inwardly beneath the rigid seams to support the same and being rigidly secured to the roof sheets on opposite sides of the seams.

25. A car roof comprising metal side plates having vertical upstanding flanges, roof sheets extending from side plate to side plate and having their ends turned down and rigidly secured to the outer faces of the upstanding flanges of said side plates, said roof sheets being connected along their side margins by rigid seams, and a combined supporting and flashing member secured to the upstanding flanges of the side plates at each of said seams, said supporting member being arranged between the down-turned ends of the roof sheets and the upstanding flanges of the side plates and having an inwardly extending portion adapted to support the sheets in the region of the seams.

26. A car roof comprising metal side plates of Z-section, said side plates being arranged with their web portions disposed horizontal, roof sheets extending from side plate to side plate, said roof sheets being connected along their side margins by rigid joints and having their ends turned down over the outer faces of the uppermost flanges

of said side plates and rigidly secured thereto, and a combined supporting and flashing member rigidly secured to the uppermost flanges of said side plates at each joint, 5 said supporting member being arranged between the down-turned ends of the roof sheets and the outer surfaces of the upper-

most flanges of the side plates and having an inwardly extending portion adapted to support the sheets in the region of the joints. 10
Signed at Parnassus, Pa., this 27th day of June, 1919.

FRANK W. WOLFF.
